UNITED STATES PATENT OFFICE.

JOSEPH FINKELSTEIN, OF BROOKLYN, NEW YORK.

CORDING-MACHINE.

1,334,086.

Specification of Letters Patent. Patented Mar. 16, 1920.

Application filed February 26, 1919. Serial No. 279,272.

To all whom it may concern:

Be it known that I, JOSEPH FINKELSTEIN, a citizen of the United States, and a resident of the borough of Brooklyn, county of 5 Kings, and State of New York, have invented certain new and useful Improvements in Cording-Machines, of which the following is a specification.

The present invention relates to cording 10 machines, the embodiment disclosed herein being particularly intended for the manufacture of covered or coated cord, that is, a cord having a twisted core or heart, and an outer covering placed there over, the 15 core, for instance, being of cotton while the outer coating is of silk. An object of the invention is to provide a machine of this character which will be efficient in operation, and with which a better product may be 20 produced, with greater facility, than has heretofore been possible.

More particular objects are to provide a 25 novel twisting means, to the end that the cording machine will be greatly simplified. breakage of the strands or threads will be eliminated to a great extent, the machine may be run at very much greater speed than has heretofore been possible, and in which breakage of the threads may be 30 detected during operation of the machine, and the bobbins may be renewed or the thread repaired without stopping the machine.

Further objects are to enable the twisting 35 of cord in either direction with the same machine and to any desired degree of tightness, and in which the cord as it is twisted is immediately taken up so that the twisting does not run down to the threads as they are fed from the bobbin.

40 A machine according to my invention consists generally of a stationary support for the bobbins, and twisting means which forms the cord and takes up the same as it is formed.

45 In such a machine centrifugal forces upon the bobbins are entirely eliminated, so that strains upon the strands and breakage is reduced to a negligible quantity. Very fine threads of silk or other substance may therefore be used without constant danger of 50 breakage and breakage of the strands may furthermore be immediately detected while the machine is running. This is not possible in those machines in which the bobbins are 55 carried by the revolving twisting means.

With the above and other objects in view,

an embodiment of my invention is shown in the accompanying drawing and this embodiment will be hereinafter more fully described with reference thereto, and the invention will be finally pointed out in the 60 claims.

In the accompanying drawing:

Figure 1 is a side elevation of a machine 65 embodying my invention;

Fig. 2 is a vertical sectional view thereof taken along the line 2—2 of Fig. 1;

Fig. 3 is a horizontal sectional view taken along the line 3—3 of Fig. 2;

Fig. 4 is an enlarged vertical sectional 70 view of a portion of the machine;

Fig. 5 is a horizontal sectional view taken along the line 5—5 of Fig. 4;

Fig. 6 is a detailed sectional view of the 75 upper end of the core guide;

Fig. 7 is a front view partly in section 80 of the core guide; and

Fig. 8 is a view of certain parts of the machine arranged to twist cord in an opposite direction.

Similar reference characters indicate corresponding parts throughout the several figures of the drawing.

Referring to the drawing, the embodiment of my invention shown therein comprises a lower stationary bobbin support A, and an upper revolving cord support and 85 twister B, adapted to twist the strands or threads as they are fed from the bobbin, and to take up and receive the twisted cord 90 gradually as it is formed.

The bobbin support consists of an upper plate or table 10 supported at its four corners upon angle-shaped standards 11, the table being provided at opposite sides with 95 semi-circular cut-out portion as at 12 and 13, to make more accessible the bobbins supported beneath the same, and which will be presently described more particularly. In spaced relation below the plate 10, there is 100 supported between the standards 11 a shelf support 14 provided centrally with an opening 15 having a porcelain bushing 16 set therein, the passage through the said bushing being slightly flared and rounded at its 105 ends.

Upon three sides of the support A and having their ends secured in the sides of standards 11, there are provided below the shelf 14 a plurality of bobbin supporting 110 rods or shafts 17, these rods at the opposed sides of the support being disposed between

and alternately of the rod at the intermediate side. Upon each of these rods there are loosely mounted a plurality of bobbin spools 18, the strands of threads 18^a from 5 which are brought downwardly through eyelets 18^b secured to the floor and respectively receiving the strands from the respective sides of the support A, the strands being carried upwardly together through the 10 passage of the bushing 16.

Upon the shelf 14 there are provided in several annular rows concentric to the opening 15 a plurality of upright posts 19. In actual practice, there is preferably a much 15 greater number of these posts than shown, and also a greater number of spools 18, but for the sake of clearness I have illustrated a relatively smaller number. Bobbin spools 20 are loosely mounted upon the posts 19. 20 Above the shelf 14, there is supported upon standards 21, a guide-plate 22 of truncated cone shape, having a central opening 23 therein relatively larger than and concentric to the opening 15, and provided at its base 25 with a lateral flange 24 having a plurality of eyelets 25 therein through which the strands 20^a from the bobbin spools 20 pass upwardly.

The strands 18^a from the bobbin spools 18, which may be called the core strands, pass 30 from the opening 15 through a guide member 26, having an open slot or groove 27 therein of semi-elliptical cross-section, the said guide being held upon an upright supporting bar 28 by means of a clamping plate 29, screws 30 disposed at each side of the member 26 connecting the said plate to the bar and tightly clamping the same in place. The member 26 is preferably square in cross-section to prevent turning.

40 The base 31 of the bar 28 is adjustably, removably and slidably mounted upon the shelf 14 beneath a slotted holding piece or strap 32 secured to the shelf by screws 33, and having in its upper side a set screw 34 45 which engages the base 31 to fixed position. The upper end of the guide member 26 is tapered as at 35, and a cone-shaped tubular cap 36 is placed there-over with a wedging fit, the core strands 18^a passing upwardly 50 through the reduced end thereof. The strands 18^a may be very readily laid in the open slot of the guide member 26, and their ends passed upwardly through the cap 36. The cap 36, as also the guide 26 may be 55 replaced when they become worn, and the adjustment of the bar 31 permits of the accurate positioning of the slot 27 relatively to the opening 15, when the same or different sized guide members are used.

60 The plate 10 is provided with a central opening 37 having an upwardly offset inwardly extending lateral plane 37^a at its periphery, to the under side of which a circular plate 38 is secured by means of bolts 65 39, the same plate being provided centrally

with an upwardly extending tubular bearing 40 tapered at its upper portion as at 41, and within the opening of which the upper capped end of the guide member 26 is disposed, the end of the cap being substantially flush with the end of the bearing, an annular space being provided about the the cap through which the strands 20^a pass exteriorly of the cap and in cone-shape, and are brought together above the cap and about the core strands 18^a passing upwardly 75 from the cap.

The revolving cord support and twister A consists of a rectangular frame 42 disposed within an inverted U-shaped standard 43 secured to the plate 12 at 44 and 45, and provided at its lower portion with a circular base 46 having at its under side a depending annular flange 47, between which and the bearing 40 there are interposed anti-friction ball-bearing sets 48 and 49. A tapered opening 50 is provided in the plate, in which the tapered end 41 of the bearing is engaged, the surfaces of the said portion 41 and the opening being placed apart 90 slightly as at 51 to prevent frictional contact.

At the upper end of the frame 42 there is provided a bearing hub 52 having a shoulder 53 within its bore. A bearing 54 is provided at the upper end of the standard 43 within which there is secured by set screws 55 a depending hanger 56, which extends through the bore at the bearing hub 52 and is provided at its lower portion with a 100 shouldered flange 57, which extends beneath the shoulder 53, anti-friction thrust bearings 58 being interposed there between, thereby revolvably supporting the frame 42. Ball-bearings 59 and 60 are interposed between 105 the cylindrical surfaces at the bore of the hub and the hanger, and thrust bearings 61 are disposed within a recess 62 at the upper end of the hub and engage the lower surface of the bearing 54. At the lower end of the 110 hanger 56, there is provided a threaded extension 63 upon which there is secured a stationary circular disk 64 disposed within the frame 42, and held against rotation by a set screw 65. Adjustment of the hanger is afforded by means of the upper threaded end 56^a upon which there is provided an adjustment nut 56^b, while the disk 64 may be adjusted by turning the same upon the 115 threaded extension 63, the set screw 65 fixing 120 the position of the same when adjusted.

Above the end of the cap 36 there is provided a groove roller 66 supported upon a bracket 67 the axis of the core strand 18^a being substantially tangential to the groove of the roller. Extra screw holes 68 are tapped into the base 46, so that the bracket may be interchangeably mounted to position the roller 66 at either side of the upwardly moving strands, the purpose of which is to 130

enable the twisting of the cord in either direction as will hereinafter more fully appear. The corded strands after twisting, pass from the roller 66 over a cylindrical 5 elongated roller 69 mounted upon a shaft 70, and thence beneath the said roller 69 to a guide roller 71 slidably and loosely mounted upon a shaft 72 having its ends supported in brackets 73 and 74 secured to 10 the plate 46. The cord then passes upwardly, to a winding drum 75 mounted within the frame 42 upon a shaft 76 having its ends secured in the upright portions of the said frame.

15 A shaft 77 is provided in the frame 42 above the drum 75, and has mounted thereon a friction wheel 78, frictionally engaging the under surface of the stationary disk 64 and adjustable along the shaft 77 20 to any position between the center and the periphery of the said disk. A beveled gear 79 is provided upon the projecting end of the shaft 77, and meshes with a beveled gear 80 provided at the upper end of a 25 shaft 81 journaled in brackets 82 and 83 secured to the frame 42, a beveled gear 84 at the lower end of the said shaft 81 meshing with a beveled gear 85 provided upon the end of the shaft 70. Pulleys 86 and 30 87 are provided respectively upon the shaft 70 and the drum 75, and are connected by a drive belt 88. The frame 42 is rotated by means of a belt 89 extending to a suitable motor (not shown) and passing over the 35 flange 47 of the base 46.

As the frame revolves, the strands 20^a and the core strands 18^a are twisted at a point between the roller 66 and the end of the cap 36, the strands 20^a twisting on and 40 sliding off evenly from the cap 36 completely covering the strands 18^a, the completed and twisted cord passing from the roller 66 to the winding drum, 75, the roller 69 and the said drum being continuously 45 rotated by the friction drive 78 to continually take up the cord as it is formed, the position of the friction drive determining the degree of twist. As the twisted cord is immediately taken up as it is formed, the 50 regular twisting action will be continuous at one point, but will not pass down to the threads being fed from the bobbin. The frame 42 may be rotated at any desired speed and by adjusting the position of the 55 friction wheel 78 relatively to the periphery of the stationary disk 64 the degree of twist of the cord may be accurately regulated.

Upon the same machine the cord may be twisted in an opposite direction by changing the position of the roller 66 as above pointed out, and carrying the cord over the pulleys 69 in an opposite direction and under a roller 90 similar to the roller 71, but disposed upon a shaft 91 supported in 60 brackets 92 and 93 at the opposite side of

the circular base 46, and thence to the receiving drum, as shown in Fig. 8 the frame being rotated in the opposite direction by reversing the belt 89. Without this arrangement the turning of the frame in the opposite direction will cause the strands to move downwardly instead of upwardly. 70

I have illustrated and described a preferred and satisfactory embodiment of my invention, but it is obvious that changes 75 may be made therein within the spirit and scope thereof as defined in the appended claims.

I claim:

1. In a cording machine, a support, a central guide carried by said support and having a single guide opening, bobbin spools, a plurality of strands from said bobbin spools adapted to pass in grouped relation through said guide, twisting means adapted 80 to revolve relative to said support and receive said strands from said guide to be twisted, the twisting point being exterior of the outlet of said guide, other bobbin spools carried by said support, guide means 85 adapted to guide the strands from said other bobbin spools exterior of said first-mentioned guide to said twisting means, the twisting point of said last-mentioned strands being coincident to the twisting point of said first-mentioned strands, 90 said last-mentioned strands annularly surrounding said first-mentioned strands, said strands adapted to be twisted at the twisting point in the same direction, said 95 last-mentioned strands adapted to be laid as a covering about said first-mentioned strands.

2. In a cording machine, a support, a central guide carried by said support provided 105 with a restricted outlet, bobbin spools, a plurality of strands from said bobbin spools adapted to pass through said guide and upwardly from said restricted outlet as a compact group, the strands being substantially 110 in parallel relation with each other, twisting means adapted to revolve relatively to said support and receive said strands from said guide to be twisted, the twisting point being exterior of said restricted outlet of 115 said guide, other bobbin spools carried by said support, an annular guide surrounding said first-mentioned guide forming an annular space exterior of said restricted outlet adapted to guide the strands from said 120 other bobbin spools exteriorly of said group strands to said twisting means, the twisting point of said last-mentioned strands being coincident to the twisting point of said first-mentioned strands, and having substantially 125 the same degree of twist, said last-mentioned strands annularly surrounding said first-mentioned strands, said strands adapted to be simultaneously twisted in the same direction, said last- 130

mentioned strands adapted to be laid as a covering about said first-mentioned strands.

3. In a cording machine, a support, a central core guide carried by said support, 5 bobbin spools, strands from said bobbin spools adapted to pass through said core guide, said core guide comprising an elongated upright member having a vertically disposed longitudinal groove therein extending from one side of said member beyond the central axis thereof and a conical tubular cap at one end of said member having a reduced orifice at the upper end coaxial with the axis of said member and 10 forming the outlet therefor, strands from said bobbin spools adapted to pass through said groove and the orifice of said tubular cap, and twisting means adapted to revolve relatively to said support and receive 15 strands from said guide to be twisted.

4. In a cording machine, a support provided with a shelf having a central opening, a core guide disposed upon said shelf above that opening, bobbin spools beneath said 25 shelf, strands from said bobbin spools adapted to pass upwardly through said central opening and said core guide to form a core, bobbin spools disposed upon said shelf about said guide, a guide member disposed 30 about said core guide and provided with a plurality of annularly arranged eyelets, strands from last-mentioned bobbin spools adapted to pass through said eyelets and about said core as it issues from said core 35 guide, and twisting means adapted to revolve relatively to said support and receive said strands from said bobbin spools to be twisted, said strands from said last-mentioned bobbin spools adapted to be twisted 40 about said strands from said first-mentioned bobbin spools.

5. In a cording machine, a support, bobbin spools supported by said support, outlet means at the upper end of said support, 45 strands from said bobbin spools adapted to pass through said outlet means, means adapted to revolve about said outlet means, a guide roller carried by said revolving means, the axis of said strands passing 50 from said outlet means being substantially tangential to the periphery of said guide roller, said strands adapted to be twisted between said roller and said outlet means to form a cord, and means adapted to enable 55 the placing of said roller at either side of said outlet.

6. In a cording machine, a support, bobbin spools carried by said support, outlet means at the end of said support, strands 60 from said bobbin spools adapted to pass through said outlet means, means adapted to revolve about said outlet means, a guide roller carried by said revolving means, said

strands adapted to be twisted between said roller and said outlet means to form a cord, 65 a feed roller adapted to receive said cord as it passes from said guide roller, friction transmission means operable by the revolving of said revolving means adapted to rotate said feed roller to feed said strands 70 from said bobbin spools, said transmission means being adjustable to vary the speed of said feed roller relatively to the speed of said revolving means to regulate the twist. 75

7. In a cording machine, a support, bobbin spools supported by said support, outlet means at the end of said support, strands from said bobbin spools adapted to pass through said outlet means, means adapted to revolve about said outlet means, a guide 80 roller carried by said revolving means, said strands adapted to be twisted between said roller and said outlet means to form a cord, a feed roller adapted to receive said cord as it passes from said guide roller, a stationary 85 plate disposed annularly and in a plane perpendicular to the axis of said revolving means, a shaft carried by said revolving means and provided with a friction roller engaging said plate and adjustable toward 90 and away from said axis to vary the speed of rotation of said shaft relatively to said revolving means, and transmission means connecting said shaft and said feed roller to rotate said feed roller to feed strands from 95 said bobbin spools.

8. In a cording machine, a bobbin support, bobbin spools carried by said support, a guide member adapted to guide a plurality of strands in grouped relation from 100 said bobbin spools, guide means adapted to engage said grouped strands exterior of said guide member and in spaced relation thereto, means adapted to cause a relative rotation between said guide means and said 105 guide member to twist the said strands at a point between said guide means and said guide member, other bobbin spools carried by said support, guide means adapted to guide the strands from said other bobbin 110 spools exterior of said guide member in annularly arranged relation about said grouped strands, the twisting point of said last mentioned strands being substantially coincident to the twisting point of the 115 first mentioned strands, said last mentioned strands annularly surrounding said first mentioned strands, said strands adapted to be twisted at the twisting point in the same direction, said last mentioned strands adapted to be laid as a covering about said first mentioned strands. 120

In testimony that I claim the foregoing as my invention, I have signed my name hereunder.

JOSEPH FINKELSTEIN.
